UNITED STATES PATENT OFFICE.

EDWIN V. NESSLING, OF CHICAGO, ILLINOIS, ASSIGNOR TO GENERAL WIRE TIE COMPANY, OF CHICAGO, ILLINOIS, A CORPORATION OF ILLINOIS.

MACHINE FOR TYING OBJECTS WITH WIRE.

1,268,383.

Specification of Letters Patent.

Patented June 4, 1918.

Application filed April 19, 1915. Serial No. 22,395.

To all whom it may concern:

Be it known that I, EDWIN V. NESSLING, citizen of the United States, residing at Chicago, in the county of Cook and State 5 of Illinois, have invented certain new and useful Improvements in Machines for Tying Objects with Wire; and I do hereby declare the following to be a full, clear, and exact description of the invention, such as will enable others skilled in the art to which it 10 appertains to make and use the same.

This invention relates to improvements in machines for tying objects with wire and relates more particularly to certain improvements 15 in specific details of construction capable of conjoint use and adapted and intended to be used conjointly with improvements in said machines invented by Rogers M. Warwick and particularly described and 20 claimed in his application for Letters Patent of the United States Ser. No. 9962, filed Feb. 23, 1913, and to be similarly used conjointly with certain improvements in object carriers for machines for tying objects with 25 wire constituting the joint invention of said Warwick and myself, and described and claimed in an application for Letters Patent of the United States Ser. No. 22,874 filed April 19, 1915.

30 The particular objects of the present invention are:

First. To provide, in a machine of the character defined, means controlled by the object to be tied for maintaining the tying 35 mechanism inoperative to tie objects unless such objects are properly presented to the same;

Second. To provide wire-guide supporting means for machines of the character defined relatively so arranged and operated 40 with respect to the plane in which the tie is formed and with respect to the path of travel of objects to be tied, as to cause the said guides when opened after the tie has 45 been formed to move out of said plane and out of the path of travel of the objects.

A further object of the invention is to provide separable wire guides and carrying 50 means associated therewith acting in conjunction and combination with formations on a rigid part of the machine for automatically closing said guides when the same are moved into operative position and holding the same inflexibly closed during the 55 time they occupy said position.

In the accompanying drawings illustrating the invention consisting in the specific improvements aforesaid I have shown so much of the object tying machine as will be necessary to a full and complete understanding of the nature, objects and operation of the aforesaid several improvements.

In said drawings:

Figure 1 is a view in side elevation of a bag tying machine and an object carrier associated therewith embodying the improvements aforesaid:

Fig. 2 is a fragmentary top plan view of the same.

Fig. 3 is a bottom plan view of the tying 70 machine proper, part of the base plate thereof being broken away.

Fig. 4 is a vertical transverse section through the tying machine on the line 4—4 of Fig. 2.

Fig. 5 is a fragmentary detail front elevation of the tying mechanism.

Fig. 6 is a view similar to Fig. 5 on an enlarged scale, the wire guides being shown in transverse section.

Fig. 7 is a detail horizontal section on an enlarged scale on the line 7—7 of Fig. 6.

Fig. 8 is a detail vertical transverse section on the line 8—8 of Fig. 7.

Fig. 9 is a view in elevation of the tie as 85 formed by the machine about an object.

The tying machine embodying my improvements includes means for feeding a predetermined length of wire forward at predetermined intervals, means associated 90 with the feeding mechanism to form the wire fed by the latter into a loop of a given size and shape, means for clamping the extreme end of the fed portion of the wire to maintain the loop in position after release of the same by the loop-forming means, means for retracting an indeterminate portion of the wire fed to contract the loop about the object and engage the latter with a predetermined and adjustable pressure, means for twisting 100 the looped portion of the wire and the body portion thereof about each other to complete the tie, and means for severing the completed tie from the body of wire, and finally forming the key on the completed 105 and severed tie for digitally opening the latter to release the object.

For details of construction of all that part of the tying mechanism not included in my invention reference will be had to the afore- 110

said application of Rogers M. Warwick, Ser. No. 9962, but said mechanism will be here briefly described to the extent necessary to a full and clear understanding of my 5 invention.

The wire feeding mechanism includes a pair of opposed wire-engaging segments carried by gears rotatable on the axes indicated by the shafts 1 and 2 in the accompanying drawings, one of said segments being indicated at 3 in Fig. 2. These segments engage wire passing between the same which is received from a suitable reel or coil disposed rearwardly of the machine on any 10 suitable support which is not illustrated, said segments being adapted to feed a predetermined length of wire during each revolution of their carrying wheels. The shaft 1 is a stud-shaft carried by a reciprocable member 4 on the bed or table of the machine movable in guides toward and away from the shaft 2 which is similarly a stud-shaft rigidly mounted in the base plate of the machine. The said reciprocable member 4 is 15 normally held to maintain the wire-engaging segments of the gears carried thereby in engaging relation to the wire. The latter passes through a tube 5 through the rotatable head 6 to the separable wire guides 20 7 at the front of the machine, said guides being adapted to cause the wire to be bent to form a horseshoe loop around an object received between the separable guides 7. Mounted upon a projection 8 on a rigid 25 portion of the base plate of the machine is an anti-friction roller 9 and opposite the same on the reciprocable member 4 is a projection 10 on which a cam 11 is pivotally mounted. One face of the latter is maintained in contact with the anti-friction roller 9, said face being stepped so that as 30 said cam is turned in one direction the portion of greatest radius of said face will bear upon said anti-friction roller 9 and effect a movement of the member 4 against the action of the springs engaging the same, thereby throwing the wire-engaging segments carried by the gears on said shafts 1 and 2 out of engaging relation to the wire 35 40 to be fed forward. A lever 12 is rigidly secured to said cam and projects from the front end of the machine into the path of objects adapted to be tied, and which are carried successively to the tying mechanism 45 by means of the rotatable carrier 13 fully illustrated and described in the aforesaid joint application of said Warwick and myself Serial No. 22,374. A helical tension spring 14 maintains said lever 12 normally 50 in position to cause the portion of greatest radius of the face of the cam 11 to bear upon the antifriction roller 9 whereby to maintain said shafts 1 and 2 separated a distance preventing said wire-engaging segments 55 60 65 from operatively engaging the wire to feed

the same forward. The said lever is turned by engagement of the object therewith to a position indicated in Fig. 3 whereby the portion of least radius of the cam face becomes opposed to the anti-friction roller 9 70 75 whereby the shafts 1 and 2 are permitted to approach each other to cause the wire-engaging segments to operatively engage the wire to feed the same forward to form a loop about the object.

The wire guides 7 together form what may be termed a horse-shoe shaped device which is separable along the vertical plane extending centrally of the closed portion and midway between the arms thereof. 80 Each member of said guide comprises two parts hinged together and capable of limited pivotal movement relatively to each other, as particularly shown in Figs. 5 and 6. The upper member of each of said parts 85 of said guide is rigid with a substantially semi-circular arm 15 and the lower member 16 of each of said parts of said guide is hinged to said arm. The hinge includes a projection 17 on the member 16 coacting 90 with a stop 18 rigid with the arm 15 to limit the opening or pivotal movement of the members 16 in one direction relatively to the rigid members 7. The said arms 15 are secured at their other ends to shafts 19 95 journaled in bearings above the normal plane of action of the wire guides and at a sufficiently high elevation to bring said shafts out of the path of travel of the object carrier and the objects carried thereby. 100 The said shafts are equipped with segmental spur gears 20 and 21, the latter describing a smaller arc than the former. The said segmental gears are of equal pitch diameter and intermesh, and said gear 20 also 105 meshes with a rack 22 on a reciprocable bar 23 which is actuated from a cam carried by a gear on the shaft 1, as more particularly shown and described in the aforesaid application of Rogers M. Warwick, Ser. No. 110 9962, and at proper intervals in synchronism with the wire feeding mechanism and other parts to cause said guides 7 to be separated and raised after each loop is formed around an object, and remain separated and 115 elevated until the next succeeding object is positioned to be tied.

Each of the members 16 of the guides 7 is equipped on its lower face with a projection 24 having an inclined lower face which 120 is adapted to strike the inclined upper face of a projection 25 carried by the guide member 26 for the wire shearing and key forming mechanism, more fully described and claimed in the aforesaid application of 125 Rogers M. Warwick. As the arms 15 swing to the position to bring the members of the wire guide 7 together, the said projections 24 of the members 16 engage the projections 25 and are thereby forced into 130

their closed positions against the upper members of said guides and are rigidly and inflexibly held in such position whereby to maintain the guide channel closed for 5 properly guiding the wire to form the loop about the object.

For further details of construction and a full and complete description of the operation of the machine embodying my said 10 improvements reference will be had to the aforesaid application, Ser. No. 9962, it being obvious that said improvements herein described and claimed are incapable of use in the specific form in which they are herein embodied except in the aforesaid machine of said Warwick, though the same may obviously be modified and varied to adapt them to any variations in construction of the said tying machine, and may 15 20 probably be also modified and varied in form to perform the same functions in connection with any other machine operating on the same general principles as the aforesaid machine of said Warwick. It will be 25 obvious that the mechanism for preventing feed of wire unless an object is presented to be tied may be utilized in the tying machine in connection with any mechanical means for presenting the object to be tied.

30 I claim as my invention:

1. In a machine for tying objects with wire, having means for feeding wire longitudinally, and wire guides comprising separable members, means for effecting separation of said wire guides and simultaneously throwing the same out of the plane in which they coact to perform their function.

2. In a machine for tying objects with wire, having means for feeding wire longitudinally, and wire guides comprising separable members, a pair of pivoted arms each carrying one of said separable members, and means for simultaneously turning said arms in respectively opposite directions to 45 separate said members and at the same time move them out of the plane in which they coact to perform their function.

3. In a machine for tying objects with wire, having means for feeding wire longitudinally, and wire guides comprising separable members, a pair of parallel shafts, mechanism for oscillating the same simultaneously in opposite directions, and an arm rigid with each shaft and each carrying one 55 of said separable members whereby to move the latter out of their active planes simultaneously with their separation as said shafts are oscillated in one direction.

4. In a machine for tying objects with 60 wire, having means for feeding wire longitudinally, and wire guides comprising separable members adapted to coact to loop the wire about an object, means for effecting separation of said wire guides and simultaneously throwing the same out of the plane

in which they coact to perform their function, whereby to permit an object to travel in the looping plane into and out of loop receiving position without contact with said members.

70

5. In a machine of the kind specified including a pair of separable wire guide members each comprising a pair of elements adapted to open and close as said members are separated and brought together whereby 75 to release a loop formed in a guide groove in said members and return to position to form another loop, separable guide members each comprising two separable elements, one element of each pair and a rigid 80 portion of the machine equipped with coacting formations adapted to engage each other as said members approach closed position for effecting closure of said elements as said members attain their active positions. 85

6. In a machine substantially as described, a pair of separable wire guide members each comprising a pair of separable elements adapted to separate as said members are separated, and means on a rigid part of 90 the machine disposed in engaging relation to one of said elements of each member for effecting closure thereof as said members approach each other.

7. In a machine substantially as described, 95 a pair of separable wire guide members each comprising a pair of separable elements, means for effecting automatic separation thereof as said members are separated, and means on a rigid part of the machine disposed in engaging relation to one of said elements of each member for effecting closure thereof as said members approach each other.

8. In a machine substantially as described, 105 a pair of separable wire guide members each comprising a pair of separable elements adapted to separate as said members are separated, and coacting means on a rigid part of the machine and on one of 110 said elements of each member disposed in engaging relation to each other to effect closure of each member as it approaches its active position.

9. In a machine substantially as described, 115 a pair of separable wire guide members each comprising a pair of separable elements, means for effecting automatic separation thereof as said members are separated, and coacting means on a rigid part of the machine and on one of said elements of each member disposed in engaging relation to each other to effect closure of each member as it approaches its active position.

10. In a machine substantially as described, 125 a pair of separable wire guide members each comprising a pair of separable elements adapted to separate as said members are separated, and means on a rigid part of the machine disposed in engaging relation to 130

one of said elements of each member for effecting closure thereof as said members approach each other, and hold the same unyieldingly closed until they are again separated.

5 11. In a machine substantially as described, a pair of separable wire guide members each comprising a pair of separable elements, means for effecting automatic separation thereof as said members are separated, and means on a rigid part of the machine disposed in engaging relation to one of said elements of each member for effecting closure thereof as said members approach each other,

10 15 and hold the same unyieldingly closed until they are again separated.

12. In a machine substantially as described, a pair of separable wire guide members each comprising a pair of separable elements adapted to separate as said members are separated, a swinging arm rigid with one element of each member, and coacting formations on the other element of each member and a rigid part of the machine adapted to engage each other as said members approach their normal positions for effecting closure of said members.

13. In a machine substantially as described, a pair of separable wire guide members each comprising a pair of separable elements adapted to separate as said members are separated, a swinging arm rigid with one element of each member, and coacting formations on the other element of each member and a rigid part of the machine adapted to engage each other as said members approach their normal positions for effecting closure of said members, said coacting formations coöperating with said arms for maintaining said members unyieldingly closed while in active position.

14. In a machine substantially as described, a pair of separable wire guide members each comprising a pair of separable elements adapted to automatically separate as said members are separated, and means on a rigid part of the machine disposed in engaging relation to one of said elements of each member for effecting closure thereof as said members approach each other, a swinging arm rigid with one element of each member, and coacting formations on the other element of each member and a rigid part of the machine adapted to engage each other as said members approach their normal positions for effecting closure of said members.

15. In a machine substantially as described, a pair of separable wire guide members each comprising a pair of separable elements adapted to automatically separate as said members are separated, and means on a rigid part of the machine disposed in engaging relation to one of said elements of each member for effecting closure thereof as said members approach each other, a swing-

ing arm rigid with one element of each member, and coacting formations on the other element of each member and a rigid part of the machine adapted to engage each other as said members approach their normal positions for effecting closure of said members, said coacting formations coöperating with said arms for maintaining said members unyieldingly closed while in active position.

16. In a machine of the kind specified, the combination with the tying mechanism and a carrier for objects to be tied, of means disposed in the path of and adapted to be engaged by an object disposed on said carrier as the same is moved into position to be tied, for throwing said tying mechanism automatically into action to tie said object.

17. In a machine of the kind specified, the combination with the tying mechanism and a carrier for objects to be tied, of spring-held means disposed in the path of and adapted to be engaged by an object disposed on said carrier as the same is moved into position to be tied, for throwing said tying mechanism automatically into action to tie said object.

18. In a machine of the kind specified, the combination with the tying mechanism and a carrier for objects to be tied, of means normally maintaining said tying mechanism inactive, said means including a part disposed in the path of and adapted to be engaged by an object disposed on said carrier as the same is moved into position to be tied, for throwing said tying mechanism automatically into action to tie said object.

19. Mechanism for tying objects with wire, including means for carrying objects to be tied successively into position relative to the tying mechanism to permit wire loops to be passed around said objects, and means associated with and controlling said tying mechanism and adapted to be actuated by engagement with the object for preventing said tying mechanism performing its function unless an object is in position to be operated upon thereby.

20. In a machine for tying objects with wire, including mechanism for feeding wire and means for forming a loop of the same around an object, the combination of mechanism for maintaining said feeding mechanism normally out of engaging relation to said wire whereby to prevent the feed thereof to form said loop, and an object carrier adapted to bring objects successively into position relative to said looping means to be inclosed in said loops formed thereby, said mechanism including a part disposed in the path of and adapted to be engaged by the object for throwing said mechanism into position to cause wire to be fed as said object is presented to be tied.

21. In a machine of the kind specified, the combination with mechanism for feed-

- ing wire and forming a loop thereof around an object to be tied, and a carrier for bringing objects successively into position to be surrounded by said loop, of means for normally maintaining said mechanism inactive, 5 said means including a part disposed in the path of and adapted to be engaged by the object as the latter moves into the aforesaid position to throw said wire feed mechanism into action to form the loop about said object.
22. In a machine of the kind specified, the combination with tying mechanism including a pair of opposed wire engaging elements adapted to engage a wire therebetween at intervals to feed a given length thereof longitudinally to tie an object, of 10 mechanism for presenting objects to be tied successively to said tying mechanism, and spring-held mechanism for maintaining said 15 wire-engaging elements normally out of engaging relation to the wire, said last mechanism including a part disposed in the path of and adapted to be engaged by objects 20 carried by said presenting mechanism for causing said wire-engaging mechanism to be moved into engaging relation to the wire whenever an object is presented to said tying mechanism.
23. In a machine of the kind specified, the combination with tying mechanism including a pair of opposed wire-engaging elements adapted to engage a wire therebetween at intervals to feed a given length 25 thereof longitudinally to tie an object, of a spring-pressed member carrying one of said elements, a spring-held part acting to force 30 said spring-pressed member to maintain said elements out of engaging relation to the wire, a lever rigid with said part, and object-presenting mechanism associated with 35 said tying mechanism, said lever projecting into the path of objects presented to said tying mechanism and adapted to be moved 40 thereby to cause said spring-pressed member to be moved to bring said wire-engaging elements into engaging relation to the wire.
24. In a machine of the kind specified, the combination with tying mechanism including 45 a pair of opposed wire-engaging elements adapted to engage a wire therebetween at intervals to feed a given length thereof longitudinally to tie an object, of a spring-pressed member carrying one of 50
- said elements, a cam pivotally mounted on 55 a rigid part of the machine, a lever rigid therewith, a spring for holding said lever and cam normally in a given position, said cam engaging said spring-pressed member and in its normal position holding the same 60 against the action of its spring to maintain the element carried thereby out of engaging relation to the wire, and object-presenting mechanism associated with said tying mechanism, said lever projecting into the path 65 of objects presented to said tying mechanism and adapted to be moved thereby to cause said spring-pressed member to be moved to bring said wire-engaging elements into engaging relation to the wire. 70
25. In a machine of the kind specified, a carrier for objects to be tied, mechanism for forming and securing a tie around each object on said carrier, gearing for synchronizing the operations of said carrier and said 75 mechanism, and means associated with the latter and controlled by the objects to be tied for rendering the same operative to perform its function as each object becomes positioned relatively thereto to be tied. 80
26. In a machine of the kind specified, a carrier for objects to be tied, normally inoperative mechanism for forming and securing a tie around each object on said carrier, gearing for synchronizing the operations of said carrier and said mechanism, and means associated with the latter and controlled by the objects to be tied for rendering the same operative to perform its function as each object becomes positioned 85 relatively thereto to be tied.
27. In a machine of the kind specified, the combination with a carrier for objects to be tied, mechanism for feeding wire, and mechanism for looping and tying the same 90 about said objects in the order of their presentation by said carrier, of means associated with said wire feed mechanism and adapted to be actuated successively by the objects to be tied for controlling the feed of wire 100 thereby.
- In testimony whereof I have signed my name in presence of two subscribing witnesses.

EDWIN V. NESSLING.
